N. Y., a corporation of Maryland

Original application January 3, 1933, Serial No.
649,777. Divided and this application November
10, 1936, Serial No. 110,080

7 Claims. (Cl. 72—124)

This invention relates to construction materials, especially construction materials of fibrous composition. The invention has particular reference to wall boards with edges preformed to particular shapes in order to provide tight joints between adjacent boards.

The problems arising in the use of construction materials which must be laid as units or elements of greater or less size include the proper formation of the joints between such elements to insure continuity of a surface to be exposed or to prevent leakage or infiltration of air through the structure, as well as to provide a proper support at the joint for superimposed surfacing materials. Especially in wall boards which are used in abutted relation to form a continuous surface of the wall is it desirable or necessary that the continuity of the finished surface shall not be marred by the joint and also that the joint shall be strong and of such form as to prevent the leakage of air therethrough, particularly when laid upon an outside wall. Moreover, the joint should be of such form in many cases as properly to support a plaster applied upon the wall board and over the joint. It is frequently necessary in such cases to provide a lock for the plaster which will assist in preventing cracking and breaking away of the plaster at the joint.

To accomplish such purposes in various types of construction materials and in wall board, it has heretofore been proposed to form the edges of the units or elements or of the wall boards with a so-called "shiplap" or rabbeted edge. Such units or boards may be laid with the rabbet of one unit lapping upon the reverse rabbet of an adjacent unit. Moreover, it has heretofore been proposed so to form such shiplap or rabbeted edges that when the units or the boards are so lapped a space of greater or less width is left between the adjacent edges of the units or boards on that side thereof which is to be exposed. This arrangement provides a recess into which plaster or other covering material may enter to form a lock for said covering material and makes possible a greater thickness of the plaster over the joint and thereby a stronger plaster joint.

The problem of expansion in such a construction, however, has not been suitably solved. While such a space as will provide for a lock in some cases will also take care of the expansion, nevertheless in many cases the abutment of the edge of one of the boards against the rabbet of the other board prevents the free expansion of the board which is necessary to prevent buckling and cracking or breakage of the plaster or cover-

ing material if such material is applied to the base surface. Moreover, the methods of producing the shiplap or rabbeted edge in many cases have been wasteful, particularly when making provision for the space to form a lock for the plaster or covering material.

One object of the present invention, therefore, is to provide a form of shiplap or rabbeted edge for covering units or for wall boards which will incorporate the features of the forms of units and wall boards heretofore proposed but which will properly take care of the expansion.

Another object of the invention is to utilize a method of making such rabbeted edge units or wall boards which will avoid waste of material and secure a production thereof at low cost.

In order to provide more effectively for the expansion which occurs in construction units and which results in buckling of the units or cracking of the surface thereof or cracking and breaking away of materials such as wall plasters applied thereto, the present invention proposes a form of rabbeted joint in which provision is made for expansion of the joint by means of a space between portions of the adjacent edges of adjacent units while other portions of the edges are in substantial abutment. The edges, however, are so formed that the portions in abutment may yield under the force of expansion without undue deformation or distortion of these portions to effect adversely the covering material applied thereto. Provision is made, therefore, both for the lock of the covering material such as plaster and for the expansion of the base unit such as a wall board. Cracking and breaking of the plaster or covering material at the joint are thereby prevented and buckling of the units, and consequent cracking of the face of the covering material or plaster which occurs when the base is not free to expand is also prevented.

The preferred method by which the product of the invention is produced comprises the severing of the material from which the unit is to be formed in such a way as to remove a minimum of material, as by a fine saw cut, and the subsequent separation of the two portions of the material along a line connecting the cuts.

Such a method is the subject of my prior application, Serial No. 649,777, filed January 3, 1933, of which the present application is a division, and provides for the formation of a rabbeted edge by making two such saw cuts transversely of the surface of the unit on opposite surfaces of said unit, said cuts being spaced from each other in a direction parallel to the

surfaces. The cuts do not extend through the unit from one surface to the other and the line of severage or cleavage substantially connects the inner ends of the two cuts in the body of the material.

The invention will be more clearly understood from the following description taken in connection with the drawing in which:

The figure shows in one embodiment of the invention an assembly of units having rabbeted edges.

In the figure is shown in cross section the application of the invention to a joint between wall boards. The wall board 1 is formed at its left hand edge in the figure with a rabbeted recess provided by the surfaces 2 and 3. The tongue 4, of which the surface 2 forms the surface to be lapped upon the rabbeted edge of an adjacent board, is formed with a bevel surface 5 extending from the V-shaped edge 6 reversely upon the tongue 4. The thickness of the tongue 4 is approximately one-half the thickness of the board 1, and correspondingly the depth of the surface 3 is approximately one-half the thickness of said board. These proportions, however, may be varied within the scope of the invention.

At the opposite edge of the board 1 and in the reverse hand from the tongue 4 is formed the tongue 10 having an end surface 11 and a longitudinal surface 12. The height of the surface 11 is approximately one-half the thickness of the board. Thus the surface 12 is about at the middle of the thickness of the board. From the inner end of the surface 12 of the tongue 10 a bevel surface 13 extends inwardly toward the center of the length of the board but outwardly toward the upper surface 7 thereof to form with the surface 12 an obtuse angle. The angle of the bevel surface 13 with respect to the upper surface 7 of the board may be substantially the same as that of the surface 5 with said upper surface 7. However, if desired, the angles of these two surfaces may be different to suit particular conditions.

It will be noted from the figure showing three such wall boards, one lapped upon the other, that the V-shaped edge 6 substantially abuts against the bevel surface 13 of the adjacent board. As the surfaces 2 and 12 are substantially longitudinally of the width of the board, these surfaces in adjacent units may move with respect to each other as in any shiplap construction. While these surfaces 2 and 12 have been shown as straight lines, they may be otherwise formed to suit different conditions provided the form of one with respect to the other is such that the overlapping tongue 4 of one board may move upon the overlapped tongue 10 of the adjacent board without substantial distortion of the tongues or substantial movement transversely of the surfaces of the boards. As the V edge of the overlapping tongue 4 moves against the bevel surface 13 of an adjacent board under the force of expansion, a slight yielding or compression or even a slight crushing of such V edge may occur. As the edge 6 presents only a small amount of material against the surface 13, such yielding or even such crushing will not produce substantial deformation of the joint and plaster or other covering material applied upon the surface 7 and extending into the recess 16 between the surfaces 5 and 13 of adjacent boards will not be subject to an extreme force which will tend to crack the plaster at the joint and to cause it to chip off or break away.

While heretofore it has been proposed to use boards presenting a recess, such as that shown at 15 in the figure, in such prior constructions the edges of the boards have been so formed that when the V edge 6 abuts the surface 13 the edge 11 will abut the surface 3 of the rabbet of the adjacent board. It has been found to be difficult to persuade workmen to leave space for expansion as it is easier to abut the boards when laying. Thus no provision has been made for expansion of the board because the abutment of the surfaces 11 and 3 prevent relative movement of said boards. In the present invention, as shown in the figure, a space is left between the end edge surface 11 of the tongue 10 of one board and the surface 3 of the rabbet of the overlapped board. When expansion of the boards takes place the edge 11 may move toward the surface 3 without bringing pressure thereon which will cause the boards to buckle or which will bring upon the joint forces which will tend to destroy the joint and cause cracking of the plaster applied thereto. It now should be clear that to provide the space between the surface 11 and the surface 3 it is necessary to form the surface 12 of the overlapped tongue 10 on one edge of the board with less length in the direction of the width of the board than the length in said direction of the surface 2. As may be seen in the figure, the difference in length of the surface 2 and of the surface 12 in the overlapped arrangement of the boards leaves the necessary space between the surface 11 and the surface 3 for expansion of the boards when the V edge is abutted against the bevel 13.

As a particular example of the proportions which are practicable for the embodiment of the invention, those suitable for a wall board may be given. For so-called insulating lath which is used as a base for plaster or stucco, sheets or panels of the standard size of 96 inches length by 48 inches width may be reduced to smaller panels of approximately 48 inches by 16 inches to form the insulating lath. The width of shiplap boards, shown in the figure by the dimension A, correspondingly would be approximately 16 inches from the V edge 6 to the corner formed by surfaces 12 and 13. As an example of the dimensions necessary for the rabbeted edges, the following may be given: For a thickness of board about $\frac{1}{2}$ " the length of the surface 2 may be about $\frac{1}{2}$ " and the length of the surface 12 may be about $\frac{1}{4}$ ", thus leaving a space of approximately $\frac{1}{4}$ " for expansion. In a board of such a thickness the depth of the surface 3 is approximately $\frac{1}{4}$ " and similarly the dimension of the surface 11 is approximately $\frac{1}{4}$ ". Thus the surfaces 2 and 12 are positioned substantially at the center of the thickness of the board. The angle of the bevel surfaces 5 and 13 may be conveniently 45 degrees or in some cases the angle which these surfaces make with the surface 7 upon which plaster is to be applied may be approximately 120 degrees. Various modifications of the dimensions may be made within the scope of the invention, and in order to insure alignment of the surfaces 7 slight clearances between the surfaces 2 and 12 may be provided for. Moreover, in different forms of units different dimensions and clearances and different angles of the bevel surfaces may be used. It will be apparent that a movement of one board with respect to the other may produce a compression or a crushing of the V edge 6 upon the surface 13 of the adjacent board but that ample space is 75

allowed between the surfaces 11 and 3 for such expansion without bringing the surfaces 11 and 3 into contact.

In order to form the V-shaped recesses or beveled surfaces which have been described above in connection with the figure, a cutter or in some cases a grinding wheel which has a form in section to provide at its rim a V of the desired angle and of the desired position with respect to the plane of rotation, i. e., whether symmetrical with said plane of rotation of said cutter or otherwise, may be used. Thus, in one operation a bevel edge board may be produced in the manner described in my prior application, Serial No. 15 649,777, filed January 3, 1933. By using in accordance with the process of said prior application a saw or cutter of proper width for the lower cut the width of the space between the surfaces 11 and 3 are shown in the figure may be 20 made such as to leave room for expansion of the boards. By suitably positioning the saws or the cutters or the grinding wheels, the dimensions desired for the surfaces 2 and 12 as well as for the relation of the other surfaces of the edges of 25 the board may be obtained.

In applying the invention in the production of units or elements of some kinds of material the cleavage or breakage of the body structure of the material along the line of cleavage may result in 30 surfaces which are not sufficiently smooth. These surfaces may result from the tearing away of fibres from one side by the other or from the interspersed relation of the particles forming the body structure, said particles having parts thereof 35 extending over the line of cleavage into the body structure on the opposite side thereof. In some cases such rough surfaces are not a disadvantage, particularly when the units or elements 40 are to be lapped again in the same position as that in which they were broken apart. In some cases, however, it may be necessary to smooth these surfaces by running the separated units or portions over an emery wheel or other device to 45 bring the rough surface down substantially to the center of the width of the board.

This is the more necessary when units such as wall boards are to be arranged upon a supporting structure without any superimposed coating such as plaster which will cover the joint, although 50 in some cases it may be also necessary to smooth the rough surface in order to insure that the exterior surfaces of two adjacent boards shall be aligned.

While the invention has been described and 55 illustrated more particularly in connection with wall boards, it is applicable to other types of construction units and construction materials, whether of granular or fibrous or other body structure. In particular, however, the invention is useful in the formation of shiplap edges on 60 panels of wall boards of fibrous materials which have not a great resistance to crushing of the edge thereof when reduced in thickness or 65 brought to a sharp edge.

What is claimed is:

1. A structural member having rabbeted edges in generally complementary relation to permit lapping one edge of one member upon the other 70 edge of another member and having one rabbet longer than the other, the shape of that portion of the member forming the longer rabbet being such as to provide an edge of relatively weak structure with respect to the remaining 75 structure of the member, which edge substantially

takes the edgewise bearing of said rabbet against the other member.

2. A structural unit having two rabbeted edges for overlapping upon the rabbeted edges of similar units, the length of the rabbet of one edge 5 of the unit being longer than that of the other edge thereof, the portion of the unit adjacent the long length of the rabbet being beveled on its exterior end surface so to form a V edge with said long rabbet that said V edge substantially 10 takes the bearing of edgewise contact between said similar units.

3. A structural unit having two rabbeted edges for overlapping upon the rabbeted edges of similar units, the length of the rabbet of one edge 15 of the unit being longer than that of the other edge thereof, the portion of the unit adjacent the long length of the rabbet being beveled on its exterior end surface to form a V edge with said long rabbet, the portion of the unit adjacent the 20 interior transverse surface of the rabbet of shorter length being beveled to form an obtuse angle with said rabbet of shorter length, the remaining transverse surfaces of the two rabbets being in 25 such relation to their respective rabbets as to provide clearance therebetween when said V edge is in contact with said obtuse beveled edge.

4. A wall board having two of its edges rabbeted in generally complementary relation to permit one edge of one wall board to be lapped upon the 30 other edge of another board, the length of the tongue of the rabbet of one edge being greater than the length of the tongue of the rabbet of the other edge, said rabbets being so formed that when the edge of the longer tongue is abutted 35 against the interior end surface of the other rabbet the tongue of said other rabbet will not abut the interior end surface of the first rabbet, said longer tongue having its abutting edge of 40 substantially less thickness than the thickness of said tongue to provide yielding contact when in said abutting relation.

5. A wall board having two of its edges rabbeted in generally complementary relation to permit one edge of one wall board to be lapped upon the 45 other edge of another board, the length of the tongue of the rabbet of one edge being greater than the length of the tongue of the rabbet of the other edge, said rabbets being so formed that when the edge of the longer tongue is abutted 50 against the interior end surface of the other rabbet the tongue of said other rabbet will not abut the interior end surface of the first rabbet, said longer tongue having its exterior end surface so formed with respect to the length of the 55 tongue as to present a relatively weak edge for abutment against said interior end surface of the other rabbet.

6. A wall board having shiplap edges, one of the tongues of said edges being longer than that 60 of the other, said longer tongue being formed with a beveled edge, the interior end surface of the other shiplap edge of said board being formed relative to said beveled edge substantially to take the bearing thereof under edgewise expansion of said wall board in two boards with their edges in lapped arrangement.

7. A structural member having rabbeted edges in generally complementary relation to permit one edge of one member to be lapped upon the 70 other edge of another member, the length of the tongue of the rabbet of one edge being greater than the length of the tongue of the rabbet of the other edge, the shape of the tongue of the longer rabbet being such as to provide an edge 75

of relatively weak structure with respect to the remaining portion of said tongue, said tongues of said rabbets being so formed with respect to each other that said weak edge of the longer tongue may contact a surface of the other rabbet of said other member but so as to provide clear-

ance between the remaining surfaces of the rabbets which would offer resistance to edgewise movement of said members with respect to each other.

GILBERT A. HOGGATT. 5
